UNITED STATES PATENT OFFICE.

CHARLES KOSHALKO, OF CLEVELAND, OHIO.

AIR-OPERATED TOY.

Application filed August 18, 1922. Serial No. 582,698.

To all whom it may concern:

Be it known that I, CHARLES KOSHALKO, a citizen of the United States, residing at Cleveland, in the county of Cuyahoga and

5 State of Ohio, have invented certain new and useful Improvements in Air-Operated Toys, of which the following is a specification.

This invention relates to an air-operated 10 toy which is an improvement on the toy set forth in my Patent No. 1,251,673, dated January 1, 1918.

The present improvements provide a simple, inexpensive and durable air-propeller 15 operated device of novel construction and operation adapted for attachment to a flag pole, cap of an automobile radiator, or to any holder, embodying a mechanical movement for operating movable parts of a figure, the latter being shown as the simulation 20 of an eagle having movable wings, preferably carrying flags, although it is to be understood that the representation of the figure may be varied as desired.

25 The present improvements provide mechanism which is simpler, more durable, and much less expensive than the operating mechanism of my Patent No. 1,251,673 and, in addition thereto, there is provided novel 30 means for automatically applying a braking action when the air velocity becomes too great.

The embodiments of the invention set forth hereinafter are susceptible of modification and the disclosure is to be considered 35 as illustrative, rather than restrictive, of the scope thereof.

In the accompanying drawings:

Figure 1 is a front elevation.

40 Fig. 2 is a rear elevation;

Fig. 3 is a side elevation; and

Fig. 4 is a detail view of a modified operating device.

The upright 1 is formed of a single piece 45 of sheet metal which is shaped to represent any suitable figure. As shown, the figure is that of the body of an eagle which is provided with a vertical slot 2.

Pivoted at 3 to the body are the wings 50 4 which have slots 5.

Preferably, the wings 4 are provided with fabric flags 6, the pins or staffs 7 of which are frictionally held in struck-up loops 8 of the wings 4, said wings being of metal. 55 By reason of this construction substitute flags can be employed whenever desired.

Projecting from the body is a bracket 19 and in this bracket and the body there is journaled a shaft 11 carrying a propeller 12 and a pinion 13.

Suitably journaled at 14 to the body is a gear 15. A connecting link or member 16 which is pivoted to the gear at 17, has a pin 18 which extends through the slots 2 and 5 so that as the gear turns, when driven by the rotation of the propeller, the wings 4 are raised and lowered, thus simulating the appearance of the flapping of wings and also causing the flags to be waved up and down. As the flags are fabric, they can 60 65 70 also fly in the breeze, presenting an attractive and pleasing appearance to the eye.

The shaft 11 is inclined and adapted for a limited sliding movement. Mounted on the shaft 11 is a friction washer 19 which 75 normally remains out of contact with the upright 1 due to the inclination of the shaft. When the wind pressure or velocity becomes too great, the shaft 11 slides and the collar 20 then forces the washer 19 against the upright 1, resulting in a braking action which slows down the number of revolutions of shaft 11 so that the device will neither become injured from too rapid operation nor operate so fast as to mar the pleasing 80 85 appearance of the movement of the wings and flags.

In Fig. 5 I have shown modified means for operating the wings comprising a pair of links 21, 22, both pivoted to the gear 15 90 at 23 and, respectively, pivoted to the wings at 24, 25. In this form, the pin 18 and slots 2 and 5 are omitted.

I claim:

1. In an air-operated toy, the combination 95 with an upright having a slot, of a pair of rockable members pivoted to the upright and having slots, a wheel, a link pivoted to, and driven by the wheel having a pin, said pin operating in the slots of the rockable 100 members and slot of the upright, and air-operated means for driving said wheel.

2. In an air-operated toy, the combination with a slideable shaft, and figure members operated by said shaft, of bodily shiftable 105 air-operated means for turning said shaft which is adapted to cause the shaft to slide when the air pressure on said means becomes sufficient for that purpose, and a brake which is operated when said shaft slides as 110 aforesaid.

3. In an air-operated toy, the combination

with an inclined slidable shaft, and figure 5 slides, said shaft, due to its inclination, normally remaining in a position to prevent members operated by said shaft, of bodily shiftable air-operated means for turning said shaft which also causes the shaft to slide when the air pressure on said means becomes sufficient for that purpose, and a brake which is operated when said shaft

10
braking action taking place.

In testimony whereof I affix my signature.

CHARLES KOSHALKO.
